Samuel ^WDickinson

United States Patent Office.

SAMUEL HODKINSON, OF LOUISVILLE, KENTUCKY.

Letters Patent No. 89,578, dated May 4, 1869.

IMPROVEMENT IN AUTOMATIC SWITCHES.

The Schedule referred to in these Letters Patent and making part of the same.

To all whom it may concern:

Be it known that I, SAMUEL HODKINSON, of Louisville, in the county of Jefferson, and State of Kentucky, have invented a new and useful Improvement in Self-Adjusting Railroad-Switches; and I do hereby declare that the following is a full, clear, and exact description thereof, reference being had to the accompanying drawings, and to the letters of reference marked thereon.

The nature of my invention consists in attaching levers four or five feet long to the sides of the rails, by bolts, on which they work loosely, and having their upper edges bevelled each way, forming inclined planes from either end, leaving them high in the middle, which causes them to project above the rails.

They also have grooves in their upper surfaces, to fit the flanges of the car-wheels, which, entering one end, pass over and press them down, thereby operating the shifting-bar, which moves the rails by the crank and link-attachments connecting it with the levers, and hence, becomes self-acting, that a train may pass either way on the straight road or the switch. One of the levers has the inside of the front end bevelled to admit the flanges of the wheel to pass between it and the rail, without pressing it down or shifting the rails before the train passes over, and having springs arranged at the sides which replace the lever again as soon as the train has passed over.

The above being a full description of my invention, I will proceed to describe its construction and operation, in which—

Figure 1 is a perspective view of the track, showing its general construction.

A are the cross-ties.

B B B are the rails of the main track.

C C are the adjustable rails.

D D are the side-track rails.

E E are the levers attached to the sides of the rails, which the flanges of the wheels press down as they pass, and which have grooves in the top, fitting the wheel-flanges, and are made of the shape and size above described, and as shown in the drawings.

F is a slot in the lever, which vibrates on a stationary pin in order to keep it in place.

G G are the iron pins shown in Figure 2, for the same purpose, and have in addition a steel spiral spring passing over them, one end resting against the head of the pins, the other against the side of the lever E, for the purpose of replacing it after the train has passed.

When it is coming from an opposite direction, it enters at the point of the lever E at H, the inside of which is bevelled off to admit the flange of the car-

wheels to pass between the lever and the rail without pressing it down, and when the train has passed, the lever is replaced against the rail by the springs G, at the sides.

I I are the cranks, which are operated by the levers E, through an attachment to them, under the rails at L L L.

K K K are the cranks which operate the shifting-bar M by the pitman N, all of which are made of iron, said cranks K K revolving on an iron pin affixed to the cross-ties A.

J J are the connecting-links between the cranks K K at one end, and the crank I at the other, connecting the levers E of the switch-tracks with the switch-rail O; and

O is the link connecting the lever E of the main track with the switch-rails.

Figure 2 is a perspective view of the lever E, with the spring-attachment, showing the spring and crank-attachment to the lever.

The above is a full description of the construction of my improvement, which is operated by the wheels of the cars passing over and pressing down the levers E, which, by crank and link-connections, operate the shifting-bar M, which shifts the rails to the desired position for the train to pass over in safety.

As may be seen, a train approaching the junction by the main track will adjust the switch so that it may run upon the main branch B, even if the switch were misplaced, and a train approaching from the opposite direction upon the main branch will operate in like manner, and the levers E attached to rails B, will be depressed, and the lever E attached to rails D, of the side-track, will be elevated. A train approaching by the side-track D will then be enabled to adjust the switch for its passage, and, at the same time, by means of the link O, will elevate the lever E of the main track, and, in passing over it, will not depress it, by reason of the bevelled point H and springs G, and the lever will remain in condition to be acted upon by the return-train, as above shown.

What I claim as my improvement, and desire to secure by Letters Patent, is—

The combination of the slotted lever E and spring G, the cranks I K, connecting-links J, J, and O, and shifting-bar M, all constructed, arranged, and operated in the manner and for the purpose set forth.

SAMUEL HODKINSON.
